A. COPONY.
RAILWAY CAR ROOF CONSTRUCTION.
APPLICATION FILED DEC. 20, 1915.

1,245,320.

Patented Nov. 6, 1917.

Inventor:

Alfred Copony,

Attnys.

W. J. Smith

UNITED STATES PATENT OFFICE.

ALFRED COPONY, OF CHICAGO, ILLINOIS, ASSIGNOR OF ONE-HALF TO CHARLES R. COOPER, OF CHICAGO, ILLINOIS.

RAILWAY-CAR-ROOF CONSTRUCTION.

1,245,320.

Specification of Letters Patent.

Patented Nov. 6, 1917.

Application filed December 20, 1915. Serial No. 67,860.

To all whom it may concern:

Be it known that I, ALFRED COPONY, subject to the Emperor of Austria, residing at Chicago, in the county of Cook and State 5 of Illinois, have invented new and useful Improvements in Railway-Car-Roof Construction, of which the following is a full, clear, concise, and exact description, reference being had to the accompanying drawing, forming a part of this specification.

My invention relates to railway car roof construction.

Among the objects of my invention are to provide such a construction which will be 15 simple, efficient, durable and yielding to accommodate itself to the racking of the car; one which will be leak proof and which will effectually keep out cinders; and to provide an improved construction using a one-piece 20 sheet metal roof without the usual supporting carlines and purlins, and in which means are provided for draining off the moisture which condenses on the inside of the roof.

25 Further objects will appear from the following description taken in connection with the appended claims.

In the drawings, in which I have shown two embodiments of my invention—

30 Figure 1 is a plan view of part of a car roof showing my improved construction;

Fig. 2 is a transverse section of the upper part of the car;

35 Fig. 3 is a detail of the connection between the edge of the roof and the side of the car;

Fig. 4 is a side elevation of part of the upper part of the car;

40 Fig. 5 is a detail of the running board and support;

Fig. 6 is a detail of the modification of the connection between the roof and side of the car;

45 Fig. 7 is a perspective view showing an end construction which may be used; and

Fig. 8 is a detail of a still further modification of the connection between the roof and side of the car.

50 Referring now to the drawings in detail, and first to the form shown in Figs. 1 to 5, I have here shown my invention in connection with a car comprising the posts 10 forming part of the side construction, and braced in any suitable manner, Z-bar side 55 plates 11 forming a connection between the

side construction and the roof, angle clips 12 forming a connection between the side construction and the Z-bars, tie rods 13 extending from one side of the car to the other to prevent the side plates from spreading, 60 a sheet metal roof 14 attached at its side edges to the upper vertical webs of the Z-bar, tie plates 15 extending transversely of the car and having their ends suitably secured to the sheet metal roof 14, as by spot 65 welding, the running board 16 extending along the top of the car, and clips 17 for supporting the running board and securing it to the car roof. The tie rods 13 may have their ends secured to the side construction 70 by being threaded, as shown at 18, and provided with nuts 19 on opposite sides of the lower flange of the side plates 11.

The car roof 14 may be made of sheet metal sections 20 suitably secured together 75 at their edges 21 as by butt welding. Each section 20 is provided with one of the tie plates 15. The tie rods 12 also assist in preventing buckling of the car roof. The clips 17 may be sections of angle iron secured to the car roof, bolts 22 extending from the clips 17 on one side of the running board, and other bolts 23 extend across beneath the running board. The side edges of the sections 20 are bent inwardly and upwardly to form channel portions 24 and are again bent downwardly to form channel portions 25, the latter of which channels receive the upper vertical web of the Z-bars 13 to which they are suitably secured, as by 80 means of bolts 26. The lower part of the channel 24 is provided with a number of apertures 27 to permit drainage of any moisture which may condense on the inner surface of the roof and run down into the 85 channel 24. A wood filler 28 is provided on top of the middle web of the Z-bar beneath the channel portion 24 to prevent 90 wearing contact between metal and metal.

It will be noted that in this construction 100 there are none of the usual carlines and purlins for supporting the roof; that the upwardly bowed shape of the roof, and also the channel portions 24, make the roof yielding to accommodate itself to the racking 105 of the car, and that the entire car roof is one integral piece of sheet metal supported solely at its side edges.

In the modification of Fig. 6, beams 11, the tie rods 12 and the Z-bars 13 are the 110

same as in the construction of Figs. 1 to 5. The roof 29, however, is not provided with the channel portions 24 and 25, but has its vertical edge portion 30 suitably secured directly to the vertical flange of the Z-bar 13 as by bolts 31.

In Fig. 7 I have shown an end plate construction which may be used, in which provision is made to allow the end plate to expand and contract slightly to permit some 10 springing of the roof 14. In this construction the end plate 32 is secured to the roof 14 in any suitable manner, and this end plate is provided with tapering corrugations 33 formed therein by stamping or in 15 any suitable manner. These corrugations will allow the end plate to spring somewhat so that the whole roof construction is a yielding one which will accommodate 20 itself to the racking of the car.

In the modification shown in Fig. 8 the roof 34 is provided with a channel portion 35 and an inwardly extending flange portion 36 which rests on a longitudinally extending beam 37 to which it is secured by 25 means of bolts 38. Channel portions 35 may be provided with drawn openings 39.

Having thus described my invention what I claim as new and desire to secure by Letters Patent is:—

1. A railway car comprising side construction for the two sides of the car and an upwardly-bowed springy sheet-metal roof extending from one end to the other of the 30 car and from one side to the other thereof and supported solely adjacent its side edges by said side construction, all the vertical longitudinal sections of a substantial portion of said sheet-metal roof being bounded by substantially straight horizontal lines and all the vertical transverse sections of 35 said sheet-metal roof being substantially identical and bow-shaped whereby the edges of said roof can spring toward each other to accommodate the racking movement of the side construction of the car.

2. A railway car comprising side construction for the two sides of the car and an upwardly-bowed springy sheet-metal roof 40 extending from one end to the other of the car and from one side to the other thereof and supported solely adjacent its side edges by said side construction, all the vertical longitudinal sections of said sheet-metal roof being bounded by substantially straight horizontal lines and all the vertical transverse sections of 45 said sheet-metal roof being substantially identical and bow-shaped whereby the edges of said roof can spring toward each other to accommodate the racking movement of the side construction of the car.

3. A railway car comprising side construction for the two sides of the car and an upwardly-bowed springy sheet-metal roof ex-

tending from one end to the other of the car and from one side to the other thereof and supported solely adjacent its side edges by said side construction, all the vertical longitudinal sections of a substantial portion of 50 said sheet-metal roof being bounded by substantially straight horizontal lines and all the vertical transverse sections of said sheet-metal roof being substantially identical and bow-shaped whereby the edges of said roof can spring toward each other to accommodate the racking movement of the car, said roof comprising upwardly-bowed sheet-metal plates extending from one side to the other of the car, adjacent edges of said plates being butt-welded together.

4. A railway car comprising side construction for the two sides of the car, and a self supporting roof comprising an integral upwardly bowed sheet metal plate extending 55 from one side to the other of said car and supported solely adjacent its side edges by said side construction, said side edges being bent inwardly and upwardly to form a channel, said channel portion being secured to said side construction to support the roof.

5. A railway car comprising side construction for the two sides of the car, and a roof comprising an integral upwardly bowed sheet metal plate extending from one side 60 to the other of said car and supported adjacent its side edges by said side construction, said side edges being bent inwardly and upwardly to form a channel, said side construction comprising two members one 65 at each side of the car to which the upwardly bent portions of said side edges are secured.

6. A railway car comprising side construction for two sides of the car, and a roof comprising an integral upwardly bowed sheet metal plate extending from one side to the other of said car and supported adjacent its side edges by said side construction, said side edges being bent inwardly and upwardly to form a channel, said side construction comprising two metal 70 members one at each side of the car, each having a substantially vertical flange to which the upwardly bent portion of said side edges are secured.

7. A railway car comprising side construction for the two sides of the car, and a roof comprising an integral upwardly bowed sheet metal plate extending from one side to the other of said car and supported adjacent its side edges by said side construction, said side edges being bent inwardly and upwardly to form a channel, said side construction comprising two members, one at each 75 side of the car to which the upwardly bent portions of said side edges are secured, said plate having openings in the said channel portions to permit drainage from the inside to the outside of the car.

8. A railway car comprising side construction for the two sides of the car, and a roof comprising an integral upwardly bowed sheet metal plate extending from one side 5 to the other of said car and supported adjacent its side edges by said side construction, said side edges being bent inwardly and upwardly to form a channel and being bent

downwardly to form a second channel, said side construction comprising two metal 10 members one for each side of the car, each having a vertical web portion secured in said second channel.

In witness whereof, I have hereunto subscribed my name.

ALFRED COPONY.
